UNITED STATES PATENT OFFICE

BENJAMIN H. ERWIN, OF MISHAWAKA, INDIANA, ASSIGNOR TO THE INDESTRUCTO TRUNK COMPANY, OF MISHAWAKA, INDIANA, A CORPORATION OF OHIO

TRUNK LOCK AND COVERED BAIL

Application filed May 7, 1930. Serial No. 450,509.

My invention relates to improvements in trunk locks and covered bail, and it more especially consists of the features pointed out in the annexed claims.

5 The purpose of my invention is to provide a combined opening and closing bail and lock; that completely covers the bail when the trunk is locked; that is free from external projections; that affords ample length of lever 10 age of the covering member to which the bail is pivoted and which carries the lock near its free end; and that provides flanged base plates on the adjacent portions of a trunk body and its cover with which the bail, 15 the covering member, and the attaching member are associated.

With these and other ends in view, I illustrate in the accompanying drawings such instances of adaptation as will disclose the 20 broad underlying features of the invention without limiting myself to the specific details shown thereon and described herein.

Figure 1 is a front elevation of an assembled lock showing the covering member partly broken away in closed position, and the bail in its pulling position.

Fig. 2 is a front elevation of the cooperating base plates with the bail and locking parts removed.

30 Fig. 3 is a front elevation similar to Fig. 1, showing the covering member raised and in section and the bail in its pushing position.

Fig. 4 is an enlarged top plan view in section of the entire device, showing the bail in 35 its pulling position. Dotted lines show changes in position of the related parts.

Fig. 5 is an inside elevation of the covering member and its associated attaching part.

Fig. 6 is a perspective view of a tension 40 spring which serves to swing out the covering member when the trunk is unlocked.

Fig. 7 is a cross section on line 7—7 of Fig. 1.

Fig. 8 is a top plan view partly in section 45 showing a modified and simpler form of bail.

Fig. 9 is a front elevation partly in section similar to Fig. 3, showing the structure illustrated in Fig. 8.

50 Fig. 10 is a detached elevation of two of

the cooperating parts viewed from their inside while disconnected from each other.

The device is applied to all types of receptacles, such as trunks, etc., in which two parts are to be held assembled and locked, while 55 permitting the parts to be forcibly pushed apart when unlocked and as forcefully pulled together preparatory to locking them against movement. In addition to these cooperating features the device completely covers the actuating bail, which in devices of this general type have not been enclosed heretofore.

As exemplified in the drawings the body of the receptacle is designated by the numeral 1, and the cover, door or lid by the numeral 2. A base plate 3 is secured to the body. It has a beveled flange 20 along its top and bottom and the rounded end, shown in Figs. 1, 2 and 3. A companion base plate 4 is attached to the part 2. Both plates are positioned in alignment with each other as shown in Fig. 2. The extreme end 30 forms an abutting edge against which the swinging bail 11 pushes when the trunk or receptacle is to be opened by pulling the free end of the covering member 6 outward. This alternative construction is shown in Fig. 4 and a simplified modification is shown in Figs. 8 and 9.

A member 5 having a rim flange 23 and a raised boss 27 is seated in the base plate 4 with its boss positioned in the recess 26 of the boss 25. A bolt 24 passes through the parts 4 and 5, and the adjacent wall of the receptacle serves to hold the parts in rigid engagement with each other. This part 5 has 80 two recesses 35 formed at its edges, as shown in Figs. 1, 3 and 5, into which the forked ends 34 of the covering member 6 are positioned. These ends 34 are pivoted on the long pin 12 reaching from top to bottom of the part 6 85 and the part 5. In this way the covering member 6 is supported by the part 5. The projections 34 have pivoted thereon the forked ends 32 of the bails 11 or 36 by means of short pins 13, as shown in Figs. 4, 5, 8 and 9. The swinging covering member 6 carries the lock 7 whose bolts 8 pass behind the base plate 3 whenever the required key is used to actuate the bolts. The casing of the lock 7 passes through the opening 17 into a recess 95 100

formed in the wall of the receptacle, as shown in Fig. 4, or a recess formed in the base plate 3, as shown in Fig. 8.

The bail 11 is first moved slightly to the left and then to the right by the covering member 6 as it is swung outward on its pivot pin 12. The bail has an opening 29 inside of a loop 19 designed to permit the lock 7 to freely pass therethrough. This action of the bail causes the loop 19 to abut the inner edge 9 of the beveled flange 30 (shown in Fig. 3) during the first part of the movement of the member 6. As the free end of this member is pulled out further from the base plate 3, the parts 1 and 2 are forcibly pushed apart, as shown in Fig. 3, at 33, when the bail 11 may be swung outward away from the curved stop 10 and the parts 1 and 2 opened to whatever extent is desired.

To close the trunk the parts 1 and 2 are brought fairly close together, so that the loop 19 will pass over the curved stop 10, when the cover member 6 is pushed inward. This causes the loop 19 to engage the curved stop 10 as shown in Fig. 1 during the first part of the movement of the member 6. Further movement of this member (see Fig. 4) causes the bail 11 to pull the parts tightly together. When the member 6 is pushed all the way in it is held in place by the lock 7.

To assist in first moving the member 6 outward after the bolts 8 have been drawn, springs 14, shown in perspective in Fig. 6, are mounted on the short pins 13 with their free ends resting on the long pin 12. Provision is also made for easily pulling the loop 19 and the bail 11 away from the curved stop 10 through a short tongue 18 which projects inwardly from the loop across the recess 31, as shown in Figs. 1 and 3.

The base plate 4 is also provided with a marginal beveled flange 21, similar to the flange 20 of the base plate 3, and the member 6 has a marginal flange 22. These flanges cooperate to entirely enclose the inner mechanism so that the front edges of the flanges 20 and 21 are almost flush with the front face of the members 6 and 5, and by reason of the flanges 22 and 23 passing inside of the flanges 20 and 21 and the closed end 30 there is no opportunity to insert a screw driver beneath the members 5 and 6 to forcibly break into the trunk. As the bolts 8 are beveled the lock 7 is self acting whenever the member 6 is moved its full distance toward the base plate 3. The base plates 3 and 4 are riveted to the walls of the trunk and, as stated, the bolt 24 serves to hold the locking, the opening, and closing means assembled as a unit.

The construction shown in Figs. 8 and 9 is a simplified form. It comprises the base plates 3 and 4. The plate 3 has a recess formed to receive the lock 7 and it also has a projection 39 over which the squared hole 38 of the shortened bail 36 passes. A bent

tongue 37 serves to make it easy to grasp hold of it when the bail is to be pulled away from the projection 39. The operation of the parts is substantially the same whether the long bail 11 or the short bail 36 is used or 70 whether the projections 10 and 30 are used (Fig. 4) or the projection 39 is used instead (Figs. 8 and 9). In either case the lock cannot be successfully tampered with and the bail is completely enclosed. In Figure 9 the full separation of the trunk halves 1 and 2 is shown at 40. It is obvious that the base plates 3 and 4 may be transposed from the body to the door and vice versa. 75

What I claim is:

1. In trunks, a pair of base plates in alignment with each other, a flange bordering the extreme outside of both plates except at their adjacent edges, a locking member having an inner flange positioned inside and adjacent to the flange of the one base plate, a supporting plate having an inner flange positioned inside and adjacent the flange of the second base plate, means for pivoting the locking member onto the supporting plate, a swinging bail pivoted to the locking member and positioned between the locking member and the first base plate, and cooperating means between the bail and said base plate adapted to hold the bail and the plate in fixed relation to each other as the locking member is moved on its pivot to move the base plates toward or from each other. 95

2. In trunks, a pair of base plates secured respectively to a stationary and a movable part of a trunk and in alignment with each other, a flange along the extreme outer edge of both plates except at their adjacent edges, a two part locking member having its edges terminate adjacent to and within the flanges of the base plates to enclose the under side of the locking member when said member engages both plates, a pivot between the two parts of the locking member joining a stationary and a swinging part, means for attaching the stationary part to the base plate of one portion of the trunk, a bail pivoted on the inside of the swinging part, a projection on the other base plate, cooperating means between the bail and the projection adapted to hold the bail and said projection in engagement with each other as the swinging part of the locking member is swung on its pivot to move the base plates toward or from each other, and a key lock on the locking member adapted to engage the cooperating base plate. 110

In testimony whereof I affix my signature.
BENJAMIN H. ERWIN.
